UNITED STATES PATENT OFFICE.

GOTTLIEB ENGHOFER, OF ATTLEBOROUGH, MASSACHUSETTS.

LOCOMOTIVE DRIVING-GEAR.

SPECIFICATION forming part of Letters Patent No. 297,921, dated April 29, 1884.

Application filed December 31, 1883. (No model.)

To all whom it may concern:

Be it known that I, GOTTLIEB ENGHOFER, of Attleborough, in the county of Bristol and State of Massachusetts, have invented a new and useful Improvement in Locomotive Driving-Gear, of which the following is a specification.

My invention relates to the running or driving gear of locomotive-engines; and the object 10 of my invention is to produce a locomotive-engine gear by means of which two complete revolutions of the driving-wheels shall be produced by one full stroke of the piston.

My invention consists in the parts and combination of parts hereinafter described and claimed.

In the accompanying drawings, Figure 1 is a side elevation of a locomotive-boiler with my improvement applied. Fig. 2 is a detached 20 view, partly in section and partly in side elevation, of the piston and my improved connections.

In the said drawings, A designates the boiler; a, the steam-dome thereof; B B, the driving-wheels, and B' one of the connecting-rods. I have shown and will describe the driving-gear upon one side of the engine only, as the gear upon both sides of the engine is alike.

Instead of placing the cylinders low down 30 at the front end of the boiler, as heretofore, I place them high up and at the rear end of the boiler, as shown at C in Fig. 1. I connect the cylinder C with the steam-dome a by the steam-pipes c' c, and the steam which enters the dome 35 through the pipe c, leading from the boiler, is directed into one or the other of the pipes c' by a four-way valve, c², which may be actuated by suitable connections from the driving-gear.

40 C' C' designate an L-shaped frame, in the upper horizontal member of which oscillates a slide, d², to which the piston-rod is attached, while in the lower member of the frame moves the slide d³, to which the crank-rod C³ is attached.

d' d' designate the two arms of a toggle-joint, which is pivoted at its upper end to projections d upon the forward corners of the frame C'. The opposite end of the toggle-joint d' is pivoted to the upper end of the crank-rod C³, 50 while its middle joint is pivotally connected to the front end of the piston-rod link C², the rear end of which is journaled upon the front end of the slide d³. The lower end of the crank-rod C³ is journaled to the crank-pin p, upon 55 which also the forward end of the connecting-rod B' is journaled.

The operation of the mechanism is as follows: Beginning the stroke with the piston-rod at its backward limit, by the time the slide 60 d² has moved half the length of the upper member of the frame C', the crank will have made a half-revolution. When the slide d² reaches the outer limit of its stroke, the crank will have made another half-revolution, and the relative 65 movements of the slide d² and the crank on the back half-stroke are repetitions of those on the forward half-stroke, the toggle-joint d' bending as far backward as forward, so that 70 two revolutions of the driving-wheels are produced by each complete return-stroke of the piston-rod.

Having thus described my invention, I claim as new and desire to secure by Letters Patent—

1. A locomotive-engine driving-gear arranged in such manner that each full return-stroke of the piston shall produce two complete revolutions of the driving-wheels. 75

2. The combination, with the cylinder and frame C' C', of the piston-rod and crank-rod 80 and the toggle-joint d'.

3. The combination, with the cylinder and the frame C' C', carrying the projection d, of the piston-rod, crank-rod, and toggle-joint, arranged and operating as described. 85

GOTTLIEB ENGHOFER.
